Attorney

UNITED STATES PATENT OFFICE.

CLOUGH W. SHELTON, OF FLOYD COUNTY, GEORGIA.

NUT-LOCK.

1,349,696.

Specification of Letters Patent. Patented Aug. 17, 1920.

Application filed April 17, 1920. Serial No. 374,607.

To all whom it may concern:

Be it known that I, CLOUGH W. SHELTON, a citizen of the United States, residing in the county of Floyd and State of Georgia, have invented certain new and useful Improvements in Nut-Locks, of which the following is a specification, reference being had to the accompanying drawings.

This invention relates to certain improvements in nut locks and has relation more particularly to a device of this general character embodying superposed nuts coacting with the opposed threads, and it is an object of the invention to provide a novel and improved device of this general character whereby the applied nuts may be effectively held against retrograde turning movement.

Another object of the invention is to provide a novel and improved device of this general character wherein the opposed faces of the applied superposed nuts are provided with registering recesses or grooves in which is adapted to be inserted a locking key, together with means whereby said key is effectively held against displacement.

The invention consists in the details of construction and in the combination and arrangement of the several parts of my improved lock whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

40 Figure 1 is a view in top plan illustrating a nut lock constructed in accordance with an embodiment of my invention;

Fig. 2 is a sectional view taken substantially on the line 2—2 of Fig. 1;

45 Fig. 3 is a vertical view in side elevation with the key unlocked; and

Fig. 4 is a view in perspective of the key herein embodied, detached, said key being in a position substantially at right angles to the position of the key illustrated in Fig. 1.

50 As disclosed in the accompanying drawings, B denotes a bolt of conventional form and which is provided at its free extremity

with the reversely threaded portions 1 and 2. N denotes a nut engageable with the inner threaded portion 1 and N' denotes a nut engageable with the outer and reversely threaded portion 2.

The opposed faces of the nuts N and N' are provided with the radially disposed dove-tail grooves 3, preferably extending from the bore of each of the nuts N and N' to the periphery thereof whereby the opposite ends of each of said grooves are open.

The nut N is provided in one of its facets and immediately below the outer end of the groove 3 with outstanding flange or web 4. The upper or outer portion of said flange or web 4 is cut-away or reduced, as at a, whereby the outer end of the web or flange 4 is provided with a lip 5 and which lip can be upset or bended by requisite impact thereon through the instrumentality of a suitable implement.

K denotes a key having its side walls provided with the substantially V-shaped grooves 6 so that the key will snugly fit within the registering grooves 3 in the opposed faces of the nuts N and N'. The key K, when applied, has its face portion extending exteriorly of the adjacent facets of the nuts N and N' and the lower or inner marginal portion of said extended part of the key K is disposed on an inward bevel 7 so that when the lip 5 is upset or bended over into contact with said bevel 7, the key K is effectively maintained against displacement. Although I prefer to bend or upset the lip 5, it has been fully demonstrated in practice that, if desired, solder may be disposed between the bevel portion 7 of the key K and the adjacent or outer face of the lip 5. With the use of solder, it is unnecessary to upset or bend the lip 5. The outer or upper face of the extended part of the key K is provided with a transversely disposed groove or channel in which a suitable tool may be engaged to withdraw or extract the key from applied position after the lip 5 has been disengaged from the bevel portion 7 by a cold chisel or other tool or after the solder has been removed.

From the foregoing description, it is thought to be obvious that a lock constructed in accordance with my invention is particularly well adapted for use by reason of

the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice except as hereinafter claimed.

I claim:

1. In combination with the shank and a pair of superposed nuts engaged thereon, the opposed faces of the nuts being provided with grooves adapted to register, the outer ends of the grooves being open, a key substantially snugly fitting within the registering grooves, and one of said nuts being provided with means for coaction with the key to hold the same against displacement, each of the grooves in the nuts being dove-tailed, the side walls of the key being correspondingly recessed.
2. In combination with the shank and a pair of superposed nuts engaged thereon, the opposed faces of the nuts being provided with grooves adapted to register, the outer ends of the grooves being open, a key substantially snugly fitting within the registering grooves, and one of said nuts being provided with means for coaction with the key to hold the same against displacement, the forward portion of the key extending outwardly of the nuts when the key is in applied position, the outer face of said extend-

ed portion being provided with a transversely disposed groove to facilitate the extraction of the key.

3. In combination with the shank and a pair of superposed nuts engaged thereon, the opposed faces of the nuts being provided with grooves adapted to register, the outer ends of the grooves being open, a key substantially snugly fitting within the registering grooves, and one of said nuts being provided with means for coaction with the key to hold the same against displacement, the forward portion of the key extending outwardly of the nuts when the key is in applied position, the inner marginal portion of said extended part being beveled.

4. In combination with the shank and a pair of superposed nuts engaged thereon, the opposed faces of the nuts being provided with grooves adapted to register, the outer ends of the grooves being open, a key substantially snugly fitting within the registering grooves, and one of said nuts being provided with means for coaction with the key to hold the same against displacement, the forward portion of the key extending outwardly of the nuts when the key is in applied position, the inner marginal portion of said extended part being beveled, one of the nuts being provided with an outstanding lip adapted to overlie said beveled portion.

In testimony whereof I hereunto affix my signature.

CLOUGH W. SHELTON.
